UNITED STATES PATENT OFFICE

RICHARD E. MIESSE, OF CHICAGO, ILLINOIS, ASSIGNOR, BY MESNE ASSIGNMENTS, TO
Q. R. S. NEON, INC., OF CHICAGO, ILLINOIS, A CORPORATION OF ILLINOIS

MULTIPLE GASEOUS CONDUCTION DEVICE

Application filed August 3, 1928. Serial No. 297,326.

My invention relates to multiple gaseous conduction devices and has for its object the provision of an improved device of this character in which a plurality of electrodes 5 are used in one tube.

The object of this arrangement is to provide a structure which is operative from the ordinary 110 or 220 volt electric circuit. The tube itself is of the vacuous type and contains any suitable gas which may be made luminous upon the application of an electric pressure. Neon is a gas which is very generally employed in this connection.

I will describe my invention more in detail 15 by referring to the accompanying drawing in which I have diagrammatically illustrated one form of tube together with its circuit connections.

I show a source of current 10 which in this 20 instance, is direct current but which may also be alternating current if desired, this source of current being preferably of the 110 or 220 volt variety. Conductors 11 and 12 lead from this source and provide the 25 necessary current for the operation of the tube 13. This tube is of the vacuous type and has within it a luminous gas such as neon at any suitable pressure, say 10 or 15 mm. of mercury.

Within the tube I provide three electrodes, which if the device is of the direct current variety as shown constitute anodes, these 30 anodes being numbered 14, 15 and 16 respectively. These anodes are all connected 35 with the conductor 11 through the interposition of resistances 17, 18 and 19, the resistances being of such order of magnitude that the current flow by way of the anode 40 through the gas is limited to about 30 milliampères. On both sides of these anodes I prefer to place electrodes which may be operated at incandescence, so as to lower the 45 break-down voltage required and to lower the cathode drop. These electrodes respectively are numbered 20, 21, 22 and 23. One terminal of each of these electrodes is directly connected to the conductor 12, thus forming a discharge path between each anode and cathode, which for instance, can 50 be placed from the conductor 12 through the

cathode 23, anode 16, resistance 19 to the conductor 11.

Resistances are included in series with each cathode, respectively the resistances 24, 25, 26, and 27. These resistances are of such 55 an order of magnitude that the voltage drop across them is sufficient to leave but four volts as the pressure across the terminals of the cathode itself. The resistance of the cathode circuit is of such order of magnitude 60 that about one-half ampere flows therethrough for the purpose of rendering said cathode incandescent.

It will be noted that by this arrangement 65 each anode serves as the electrode for a gaseous current stream in two directions. The anode 14 permits a discharge to the cathode 20 and also to the cathode 21 and the cathode 21 is in the discharge path not only 70 of the anode 14, but also of the anode 15. There is thus a multiple discharge from each 75 of the electrodes with the exception of the two end electrodes. By reason of the fact that I use an incandescent cathode and that I use a relatively short gap between the electrodes of opposite sides, I am enabled to cause the illumination of a tube of considerable length even though the applied electric pressure may be no more than 110 or 220 80 volts.

From what has thus been described, the 85 nature of my invention will be readily clear to those skilled in the art and it will also be clear that many modifications may be made within the spirit of my invention.

Having, however, thus described one form 85 which my invention may take, what I claim as new and desire to secure by Letters Patent is:

1. An illuminating device of the character 90 described comprising an elongated envelope having therein a filling of gas adapted to become luminous when conducting electricity, a series of electrodes spaced longitudinally 95 of said tube throughout its length, certain 95 of said electrodes having a pair of leads and others having a single lead only, and a common source of current having one lead of each pair of leads connected to one side thereof and the other lead of each pair connected 100

to the other side thereof through a suitable resistance and having the single leads connected to one side of the current source through a suitable resistance whereby said 5 two lead electrodes are caused to glow and the gas between said electrodes is subjected to a sufficient potential to cause it to conduct electricity.

2. An illuminating device of the character 10 described comprising an elongated envelope having therein a filling of gas adapted to become luminous when conducting electricity, a series of electrodes spaced longitudinally of said tube throughout its length, alternate 15 electrodes having a pair of leads and others having a single lead only, and a common source of current having one lead of each pair of leads connected to one side thereof and the other lead of each pair connected to 20 the other side thereof through a suitable resistance and having the single leads connected to one side of the current source through a suitable resistance whereby said two lead electrodes are caused to glow and the gas between 25 said electrodes is subjected to sufficient potential to cause it to conduct electricity.

In witness whereof, I hereunto subscribe my name this 20th day of July, A. D. 1928.

RICHARD E. MIESSE.
